Primary Examiner—Nelson C. Holtje

(21) Appl. No.: **29/141,035**

(57) **CLAIM**

(22) Filed: **Apr. 30, 2001**

The ornamental design for a low pressure fluid flow control valve, as shown and described.

(51) LOC (7) Cl. **23-01**

DESCRIPTION

(52) U.S. Cl. **D23/233**

FIG. 1 is a side, cylindrically symmetric about its long axis, view.

(58) Field of Search D23/233, 235-237,

FIG. 2 is a nearly end-on, fluid exit port with slotted vent cover, view.

D23/229, 244-249; D24/129; 251/309-310;
137/819, 527.2, 527.4, 527.8, 549-550,
854

FIG. 3 is a nearly entrance end-on view with hole where fluid flows in

(56) **References Cited**

FIG. 4 is an isometric view from the exit end, showing a hole-perforated, air filter vent cover against the shoulder

U.S. PATENT DOCUMENTS

FIG. 5 is a isometric drawing which views from the entrance port at the right side of the rendering; and,
